UNITED STATES PATENT OFFICE.

SIMON S. LEHMAN, OF MARTICVILLE, AND CHRISTIAN K. HERR, OF WEST LAMPETER, PENNSYLVANIA.

CAR-COUPING.

SPECIFICATION forming part of Letters Patent No. 406,103, dated July 2, 1889.

Application filed February 6, 1889. Serial No. 298,922. (No model.)

To all whom it may concern:

Be it known that we, SIMON S. LEHMAN, of Marticville, and CHRISTIAN K. HERR, of West Lampeter township, both places in the county 5 of Lancaster and State of Pennsylvania, citizens of the United States, have invented certain Improvements in Car-Couplings, of which the following is a specification.

Our invention relates to improvements in car-couplings, and is an improvement on a coupling for which Letters Patent No. 394,584 were issued to us by the United States December 18, 1888.

This invention consists in the combination, 15 with an automatically-movable sliding block located in the draw-head, as described in the said patent, of a roller pivoted in the bottom of the draw-head and upon which the sliding block rests when the coupling is linked with another, the link and coupling-pin, a yoke for raising the pin when the coupling is to be engaged with the link of another draw-head, and a lever for operating the yoke.

This invention consists, further, in the combination, with the said lever and a pin located 25 behind the sliding block and which holds the link in the draw-head, of a movable plate or bearing, against which the end of the link rests, so connected with the lever as to be moved by the same.

In the accompanying drawings, which form a part of this specification, Figure 1 is a side view of one of our couplers, the yoke being raised so as to lift the coupling-pin into position to be engaged with the link of another coupling. Fig. 2 is a view similar to that shown in Fig. 1, but with the yoke down and the coupling-pin and sliding block in position to permit the draw-head to be coupled with 35 another. Fig. 3 is a longitudinal vertical section of a draw-head having the coupling-pin engaged with the link of another draw-head.

Fig. 4 is a longitudinal horizontal section of a draw-head with the parts in position as shown in Fig. 3. Fig. 5 is a central vertical section of the rear end of a draw-head, showing the opening for the king-bolt. Fig. 6 is a top view of the draw-head, and Fig. 7 a rear end elevation of the same. Fig. 8 is a front 45 end elevation of our coupling, and Fig. 9 a

view of a hook-shaped link having an eye in each end.

A represents the draw-head, having a slot 1 in the top plate *a* to receive the upper guiding-flange 2 of the sliding block B, and a slot 55 3 in the bottom plate *a'*, in the sides of which is journaled the roller C. The rear under edge of the block B is curved or sloped upward and backward from the front and rests upon the roller C, so that it will, unless opposed, slide forward and project its tongue *c* under the coupling-pin opening 4 in the top plate. In our previous patent the sliding block B rests upon a rigid base, on which its movement is liable to be impeded by reason 60 of the accumulation of dirt, frost, or ice.

In the front of the draw-head there is a vertically-movable yoke D, located above the bull-nose, upon which the head of the coupling-pin E rests. It is supported by vertically-movable rods *e*, connected below the bull-nose by a bar F, to which the power to raise the yoke and its supports is applied. The upward movement of the yoke carries 70 with it the coupling-pin, and such movement 75 is of such extent as to clear the pin from the opening in the front of the draw-head. This removal of the coupling-pin from that opening permits the sliding block B to move forward, its tongue *c* projecting under the coupling-pin opening in the top plate *a* and there supporting it until the block is pushed back.

G is a rock-shaft passing transversely under the car and beneath the draw-head, supported by hangers 7. Upon one or both sides of the 85 car there is a handle or lever-arm *g*, attached to the shaft G, by which it is operated, and this arm is thrown into engagement with a rack on the side of the car, so as to hold it in any 90 position desirable, for the purpose to be explained.

A pin H, set in the draw-head back of the sliding block, holds the coupling-link I in place. The link normally bears on the pin H when there is any strain put upon it; but 95 when forced farther back into the draw-head it strikes against the plate K, set up in the draw-head and movable back and forth longitudinally therein. This plate is a partition covering the entire opening of the draw-head, 100

and is serrated transversely to afford a rest for the end of the link at different elevations, as shown at 6.

A rod L passes through the plate K from 5 one side of the draw-head to the other, the ends of which are received in slots m of the connecting-plates M. The plates M are pivotally secured to the ends of arms N, rigidly attached to the rock-shaft G. By means of 10 the rock-shaft, the handles, the arms N, and the plates M, the plate K is moved back and forth, permitting, when desirable, the link to be pushed back entirely into the draw-head before the cars are coupled, to prevent it from 15 being mashed or brought into contact with the face of an approaching bull-nose. To the center of the rock-shaft there is a lever-arm O, rigidly attached in such position as to be brought into contact with the bar F and raise 20 the yoke and coupling-pin when the rock-shaft is turned to move the bearing-plate K backward in the draw-head.

In order that it may not be necessary to increase the length of the draw-head, and that 25 at the same time the yoke may be raised sufficiently to clear the coupling-link from the draw-head, the ends of the rod L rest loosely in slots m in the plates M in such position that when the rock-shaft is turned to raise 30 the yoke and push the bearing-plate K back the outer ends of those slots engage the ends of rods L at such time that the upward movement of the yoke and the backward movement of the plate K may be completed simultaneously. Of course the length of the slots 35 m must be varied to conform with the proportions of the other parts of the draw-head. Should it be necessary or advisable after the coupling-pin has been raised so as to be supported by the sliding block and the yoke dropped to its normal position to push the link back into the draw-head, as when our draw-head is to be coupled with any ordinary draw-head or one having a link or hook un- 40 removably connected with it, the bearing-plate K can be moved back sufficiently far for the purpose without disturbing the coupling-pin, for after that pin is first raised and the sliding block B passes beneath it, it can 45 only drop into its normal position by pushing that block back. When the backward movement of the plate K is completed, the lever-arms g are thrown into engagement with racks on the side of the car.

50 If it is desirable that in the movement of the plate K for the purpose just described the head of the coupling-pin should not be engaged by the yoke, the parts of the draw-head may be so proportioned that the extent 55 of the backward movement of that plate may be somewhat greater when the yoke is thrown up to raise the coupling-pin than is necessary.

The rod L may be taken out upon the removal of the pins l, (shown in Figs. 4,) which hold the plates M in place. There may also be vertical recesses made in the face of the

bearing-plate K of such size as to receive the eyes 8 of the hook-link 9, (shown in Fig. 9,) so that they can be engaged by the rod L when 7c the plates M and the bearing-plate K are connected, whereby the link may be moved back and forth with and by the bearing-plate.

To prevent lateral movement of the bearing-plate K, the draw-head is provided with 75 side plates P, having horizontal slots p, through which the rod L passes. The draw-head is also provided with openings R in the rear end, as shown in Figs. 5, 6, and 7, by which a headed king-bolt may be connected 80 therewith or an ordinary king-bolt inserted.

To hold the rod L in place and keep the bearing-plate K from being forced back accidentally by the link in coupling, latches S are pivoted to the outer faces of the sides P, the 85 front ends of which are constructed to catch over the rod L when it is in its most forward position, as shown in Figs. 2 and 4. The front end of each of these latches is provided with a pin t, which projects outward 90 over the top of the plate M adjacent to it. The upper surfaces of the plates M are cam-shaped, so that as those plates move backward they act upon the pins t to raise the latches and disengage them from the rod L 95 before the ends of the slots in the plates M engage that rod, as shown in Figs. 1 and 6.

It will be seen that in our new coupling, as shown and described in this specification, a bearing is provided for the sliding block, 100 which makes both its forward and backward movement more easy and sure than it is in other draw-heads working upon the same principle, and that by a single mechanism the force is applied whereby the coupling-pin 105 is raised and a plate in the draw-head moved backward to permit the whole coupling-link to be received in the draw-head.

Having thus described our invention, what we claim as new, and desire to secure by Letters Patent, is—

1. The combination, with the draw-head, of the sliding block, a roller pivoted in the bottom of the draw-head and upon which the sliding block rests, the coupling link and pin, 115 a yoke for raising the pin when the coupling is to be engaged, and a lever for operating the yoke, substantially as and for the purpose specified.

2. In a draw-head, the combination, with 120 the coupling-pin and a yoke for raising the same, of a movable plate which forms a bearing for the rear end of the coupling-link and a device whereby the yoke may be raised and the said plate moved backward or forward, 125 substantially as and for the purpose specified.

3. In a draw-head, the combination, with 130 the coupling-pin, the yoke for raising the same, and a movable bearing-plate for the rear end of the link, of the rock-shaft, mechanism for operating the same, and connections between the rock-shaft and the yoke and bearing-plate, whereby the shaft may

raise the yoke and move the plate longitudinally in the draw-head, substantially as and for the purpose specified.

4. In a draw-head, the combination, with the yoke for raising the coupling-pin and the movable bearing-plate for the inner end of the coupling-link, of the rock-shaft, a lever for engaging with and raising the yoke, plates M, connected with the rock-shaft and provided with longitudinal slots, and projections from the sides of the said bearing-plate which engage the longitudinal slots in the plates M, all arranged and constructed substantially as and for the purpose specified.

15 5. In a draw-head, the combination, with the movable plate placed therein as a bearing for the inner end of the coupling-link and the rock-shaft, of slotted plates M, pivotally connected with the rock-shaft, and projections from the sides of the said bearing-plate

which engage the longitudinal slots in the plates M, substantially as and for the purpose specified.

6. In a draw-head, the combination, with the rock-shaft and the bearing-plate for the rear end of the coupling-link, of slotted plates M, connected with the rock-shaft, projections from the sides of the bearing-plate which engage the slots in the plates M, and latches adapted to engage the projections from the sides of the bearing-plate when occupying its most forward position, the upper edges of the plates M being constructed to raise the latches as the said plates are moved backward, substantially as and for the purpose specified.
